DRILL CRADLE

Hilmer A. Gillerstrom, Arcadia, Calif., assignor
to Independent Pneumatic Tool Co., Aurora,
Ill., a corporation of Delaware

Application October 29, 1949, Serial No. 124,281

1 Claim. (Cl. 255—51)

1

The present invention relates to the field of drilling in general and particularly to drills used in mining operations in which a positively actuated tool of the percussive or rotary type is supported upon a vertical sinker leg or column to be advanced horizontally or substantially horizontally into a wall. More specifically the invention comprises a cradle for a drill used in mining operations which is so constructed and arranged as to enable the tool readily to be mounted upon the support element and in use to be angularly adjusted about both horizontal and vertical axes.

Drills of the rotary or percussive type used in mining operations are usually too heavy to be held by the operator as they advance into the material being worked upon. Conventionally such tools are supported upon an extensible column which in one well known form is called a sinker leg. Such a column is disclosed in co-pending application Serial No. 71,064.

In the drilling operation as the tool is advanced into the work the supporting sinker leg or column pivots forwardly and its angular position changes with respect to the tool. This advance requires not only that the sinker leg be extensible but additionally that the drill be so mounted that the relative angular relationship can change as the drill advances.

The drill itself is adapted for various operations and should be removably mounted upon the sinker leg. The mounting cradle constructed in accordance with the present invention permits the drill to be removed readily, yet securely locks it in place in the operative relationship.

With an appreciation of the problems present in the field of mining, to which the present invention relates, and also of the desirability of providing an angularly adjustable and easily installed mounting, it is an object of the present invention to provide a drill cradle which effectively connects a drill to a sinker leg or similar supporting member for limited universal movement.

It is another object of the invention to provide a drill cradle in which a percussive or rotary drill adapted for mining is removably supported for angular movement about a plurality of axes.

A still further object of the invention is to provide a cradle for rotary or percussive drills which is readily positioned upon a sinker leg and which mounts the drill for limited angular movement about a horizontal axis.

These and other more specific objects will appear upon reading the following specification and claim and upon considering in connection therewith the attached drawing to which they relate.

Referring now to the drawing in which a preferred embodiment of the invention is illustrated:

Figure 1 is a side elevational view of a pneumatic drill mounted upon a sinker leg by a cradle unit constructed in accordance with the present invention;

Figure 2 is an enlarged view of the cradle unit looking in the direction of the arrows upon the line 2—2 of Figure 1, certain parts being broken away and shown in section; and

Figure 3 is a section upon the line 3—3 of Figure 2.

Referring again to the drawing, a pneumatic drill, indicated generally by the reference character 10, is illustrated and is seen to be supported upon a pneumatic sinker leg, indicated generally at 11, by a cradle unit constructed in accordance with the present invention and generally indicated at 12. Air conduits 13 and 14 from a suitable source of air under pressure connect to the drill and to the leg, respectively, and provide the necessary motive power to actuate those elements.

Drill 10 may be of conventional construction, its working parts and controls forming no part of the present invention, it being necessary only that it have a rigid casing. Such drills are usually rather elongated with approximately cylindrical bodies. The sinker leg 11 may also be conventional so long as its upper end is provided with a post, as indicated at 16, from which extends a radial pin 17.

The cradle unit constructed in accordance with the present invention comprises a cradle proper or base 21 formed in its upper surface with a downwardly recessed seat 22 from the opposite sides of which extend lateral arms 23. A pair of spaced ears 24 extend downwardly from base 21. A pair of studs or bolts 26 extend upwardly from the arms 23 in which they are threadedly seated in fixed relationship, their upper ends being threaded and adapted to seat retaining nuts 27. A clamp plate 28 extends between studs 26 and is formed with a downwardly opening V-shaped seat 29 positioned between laterally extending parallel ends or arms 31 bored to seat slidably upon the studs 26. Washers 32 are positioned between the nuts 27 and the arms 31 of the clamp. Tightening the nuts forces the clamp downwardly against drill 10 and the latter against the cradle seat 22, the relationship being as illustrated in Figure 2.

Ears 24 on the underside of cradle 21 extend upon opposite sides of and seat the transversely bored upper end 34 of a socket member 37 the lower portion of which is formed interiorly with

a seat 38 rotatably enclosing the upper end of post 16 at the top of sinker leg. Socket member 37 is provided with a downwardly opening slot 39 at its lower end which provides an entrance through which the post-carried pin 17 can pass in entering an enlargement 41 in socket seat 38. The enlargement is defined at its upper end by a shoulder 42 and at its lower end by a shoulder 43 positioned as to abut and limit the longitudinal displacement of pin 17 in the enlargement 41. In the preferred form illustrated the pin would never strike upper shoulder 42 as the upper end of post 16 contacts the inner end of seat 38. Enlargement 41 encircles post 16, and it is clear that socket member 38, and with it the entire cradle unit, may rotate relative to the post, the pin 17 traveling in the enlargement in all angular positions.

The downwardly extending ears 24 of cradle 21 are provided with transverse bores 46 and 47, and the upper portion 34 of socket member 37 positioned therebetween is formed with aligned bores 48 and 49, a transverse headed lock bolt 50 seating within the bores. The reduced threaded outer end of bolt 50 extends through the bores 46 and 49, which are enlarged, and carries a compression coil spring 51 and a bearing element 52 rotatable in ear bore 46. A lock nut 53 forces the bearing element 52 inwardly against spring 51 and draws the headed end of the bolt against the outer face of adjacent ear 24. The shank of bolt 50 is enlarged in its extension through bores 47 and 48 and seats without looseness. The adjacent faces of the ear 24 and the upper portion 34 of the socket member 37 are forced together between the bolt head and the spring 51, the latter exerting a force of sufficient magnitude to prevent relative pivotal movement between the cradle proper 21 and the socket member 37 in the absence of a pivoting force of predetermined magnitude.

In the operation of a drilling unit incorporating a cradle constructed in accordance with the present invention the drill is mounted upon a supporting leg or column as illustrated in Figure 1. The drill 10 is clamped in the concave seat 22 of cradle proper 21 by clamp member 28 which is forced thereagainst by the tightening of nuts 27 on studs 26. In positioning the drill and cradle upon the upper end of the sinker leg the socket member 37 is advanced downwardly upon the post 16 so that the post-carried pin 17 passes upwardly through the slot 39 and into the enlarged seat 41. A slight rotation angularly displaces the pin from slot 39 and positions it in enlargement 41 of post seat 38 to prevent separation.

The assembled unit is then positioned relative to the work, the conventional control valves being adjusted as to direct actuating air to the drill and to the supporting legs 11, and the unit is ready for operation. As the drill advances into the work the leg 11 pivots forwardly, the relative angular movement taking place about the pivot bolt 50 connecting the cradle proper 21 and socket member 37. If it is desired for any reason to rotate the drill about a vertical axis without turning the leg 11 the action is permitted by turning the drill cradle and socket member 37 upon the post 16, the post-carried pin 17 traveling arcuately within the enlargement 41 of post seat 38. Upon completion of the drilling operation, it being desired to separate the drill from its supporting leg, it is only necessary to rotate the drill rela-

5 tive to the leg until the post-carried pin 17 is opposite the slot 39 in socket member 37 at which time the drill can be lifted free.

While the particular apparatus herein shown and described in detail is fully capable of attaining the objects and providing the advantages hereinbefore stated, it is to be understood that it is merely illustrative of the presently preferred embodiments of the invention and that no limitations are intended to the details of construction or design herein shown other than as defined in the appended claim.

I claim:

20 A cradle unit adapted to support a drill for angular adjustment upon the upper end of a supporting leg, said unit comprising a cradle body formed in its upper surface with a drill seat, a pair of threaded studs extended upwardly from said body and from opposite sides of said seat, a clamp plate extended between said studs and overlying said seat of said cradle body, a pair of threaded nuts threadedly seated upon the upper ends of said studs and adapted to force said clamp plate toward the seat of said cradle body to secure a drill fixedly therebetween, a pair of spaced parallel ears extended downwardly from the underside of said cradle body, a socket member having a downwardly opening seat to receive a post at the upper end of a supporting leg and including an upper portion extended between said ears, said upper portion of said socket member being bored and counterbored, said ears being formed with bores aligned with the bore and counterbore in said socket member, 30 the bore in the ear adjacent the counterbore in said socket member being of the size of said counterbore and the bore in the ear adjacent the bore in said socket member being of the size of said bore, a headed bolt extended through the aligned bores and counterbores of said socket member and said ears with its threaded end projecting beyond the ear adjacent the counterbore in said socket member, said bolt having a body rotatably seating in the bore in said socket member and in the ear adjacent said bore, a resilient member encircling said bolt within said counterbore in said socket member, a sleeve concentric to said bolt abutting said resilient member and extended outwardly through the ear adjacent said counterbore, and a nut threaded on the end of said bolt abutting said sleeve and adapted to force said sleeve against said spring to compress the latter to enable it to force said socket member against the ear adjacent the headed end of said bolt to provide a frictional contact which may be varied by tightening or loosening said nut and for the purpose of controlling the resistance to relative angular adjustment between said socket member and said cradle unit.
